AUTOMATIC TAPE PLAYBACK APPARATUS

BACKGROUND OF THE INVENTION

Field of the Invention

This invention relates to an automatic tape playback apparatus in which cartridges loaded with recorded tapes are piled up in order of a program and the tapes are automatically played back one after another. More particularly, the present invention is directed to an automatic tape playback apparatus which is adapted so that a plurality of cartridges piled up in order are automatically brought to right and left playback positions; each cartridge is automatically put in its operative condition; one end portion of the tape wound on a reel in each cartridge is drawn out therefrom; the tape is automatically wound on a takeup reel for reproducing signals recorded on the tape and is thereafter rewound on the reel of the cartridge; and the cartridge is brought out of the playback position into a cartridge housing case.

SUMMARY OF THE INVENTION

One object of this invention is to provide an automatic tape playback apparatus capable of stable and accurate automatic playback with presently available tapes and reels.

Another object of this invention is to provide an automatic tape playback apparatus which is adapted so that tapes loaded in cartridges previously arranged in order of a program are automatically played back one after another in accordance with instructions given by manual remote control or the like.

Another object of this invention is to provide an automatic tape playback apparatus which can be used with presently available reels.

Another object of this invention is to provide an automatic tape playback apparatus adapted to employ cartridges suitable for use in automatic playing which use usual reels and tapes.

Another object of this invention is to provide an automatic tape playback apparatus in which tape cartridges are piled up in order of a program and are sequentially brought to right and left playback positions for sequential and continuous playback of the tapes.

Another object of this invention is to provide an automatic tape playback apparatus for use with the aforementioned cartridges.

Another object of this invention is to provide an automatic tape playback apparatus which employs a takeup reel of a specific structure adapted for use in automatic tape playback.

Another object of this invention is to provide an automatic tape playback apparatus which employs means for adjusting the position of a takeup reel.

Another object of this invention is to provide an automatic tape playback apparatus which employs a tape clamer for drawing out a tape loaded in a tape cartridge.

Another object of this invention is to provide an automatic tape playback apparatus employing a two-capstan-type tape drive system which is free from wow and flutter.

Another object of this invention is to provide an automatic tape playback apparatus which employs a specific structure of means for rewinding a tape on a reel housed in a cartridge.

Another object of this invention is to provide an automatic tape playback apparatus which employs means for indicating whether a tape is loaded in the cartridge or not and whether signals are recorded on the tape or not.

Another object of this invention is to provide an automatic tape playback apparatus which employs a cartridge provided with means for changing the position of the reel shaft according to the size of a reel used, permitting the use of usual reels irrespective of their size.

Still another object of this invention is to provide an automatic tape playback apparatus which is provided with means for bringing cartridges into cartridge housing case after their tapes are played back.

Other objects, features and advantages of this invention will become apparent from the following description taken in conjunction with the accompanying drawings.

BRIEF DESCRIPTION OF THE DRAWING

FIG. 1 is a side view schematically illustrating the general arrangement of an automatic tape playback apparatus of this invention;

10 FIG. 2 is a front view schematically illustrating one example of the automatic tape playback apparatus of this invention, with its front cover being left out;

FIG. 3 is a cross-sectional view taken along the line III-III in FIG. 2;

15 FIG. 4 is a plan view taken along the line IV-IV in FIG. 2;

FIG. 5 is a side view schematically illustrating, by way of example, the principal part of a cartridge transfer unit of this invention;

20 FIG. 6 is a side view of a shifting support depicted in FIG. 5, illustrating it in its one operative condition;

FIG. 7 is a schematic diagram showing the relationship between a cartridge support plate usable in this invention and a rewinding motor disposed opposite to the support plate;

25 FIG. 8 is a cross-sectional view taken along the line VIII-VIII in FIG. 7;

FIGS. 9 to 11 are side views of the cartridge support plate in its operative conditions;

FIG. 12 is an enlarged cross-sectional view of FIG. 9;

30 FIG. 13 is a plan view of one example of a cartridge usable in this invention;

FIG. 14 is a plan view of another example of the cartridge usable in this invention;

FIG. 15 is a cross-sectional view taken along the line XIV-XIV in FIG. 14;

35 FIG. 16 is a side view of cartridges each having a window used in the present invention;

FIG. 17 is a plan view, partly in cross section, illustrating a modified form of the cartridge usable in this invention;

40 FIG. 18 is a schematic diagram for explaining the cartridge shown in FIG. 17;

FIGS. 19A to 19C are schematic diagrams illustrating rotors for driving a reel disposed in the cartridge depicted in FIG. 17;

FIG. 20 is a plan view showing one example of a tape playback unit used in this invention;

45 FIG. 21 is a plan view illustrating, by way of example, a takeup reel used in this invention;

FIG. 22 is a cross-sectional view taken along the line XX-II-XXII in FIG. 21;

50 FIG. 23 is a plan view showing another example of the takeup reel usable in this invention;

FIG. 24 is a perspective view of the principal portion of the reel depicted in FIG. 23;

55 FIG. 25 is a plan view of the reel shown in FIG. 23, illustrating its condition when the tape is rewound;

FIG. 26 is a schematic diagram for explaining the operation of the takeup reel of this invention;

FIG. 27 is a plan view for explaining the operation of a tape clamer used in this invention;

60 FIG. 28 is a schematic plan view illustrating one example of means for controlling the rotational position of the takeup reel used in this invention;

FIG. 29 is its side view, partly in cross section;

FIGS. 30A to 30C are schematic diagrams for explaining the 65 operation of the takeup reel at its rotational positions;

FIGS. 31 is a schematic diagram illustrating the tape clamer at its one position;

FIG. 32 is a bottom view illustrating one example of the tape clamer usable in this invention;

70 FIG. 33 is its perspective view;

FIG. 34 is a front view showing another example of the tape clamer usable in this invention;

FIG. 35 is its side view;

75 FIG. 36 is a plan view showing a tape detecting means used in this invention;

FIG. 37 is a plan view of the principal portion of the tape detecting means;

FIG. 38 is a front view showing one example of a contactor of the rotary arm of the tape detecting means depicted in FIGS. 36 and 37;

FIG. 39 is a schematic diagram illustrating a drive device of a two-capstan drive system employed in this invention; and

FIG. 40 is a schematic diagram illustrating another example of the drive device.

DESCRIPTION OF THE PREFERRED EMBODIMENTS

Figure 1 is a side view of the automatic tape playback apparatus of this invention, schematically illustrating general arrangements of respective units for the purpose of facilitating a better understanding of the invention. Reference numeral 1 indicates generally a rack, on the front surface of which are provided a door 2 of a case for housing cartridges after their tapes are played back, a front door 3 and a door 4 for a control unit. Reference numerals 5 and 6 respectively designate exhaust fans and suction fans disposed on the inside of upper and rear plates of the rack 1. The rack 1 has incorporated therein a power source unit 7, a cartridge transfer control unit 8, a control panel indicating unit 9, an audio control amplifying unit 10 and so on. Since they are well known in the art and are not directly related to this invention, no detailed description will be given in connection therewith.

As illustrated in Figure 1, the automatic tape playback apparatus of this invention comprises a lift unit 100 having a plurality of pairs of lift guides for carrying cartridges, a lift drive unit 200 for driving the lift unit 100, a cartridge transfer unit 400 including cartridge transfer screws 401 for bringing the cartridges 300 to the playback positions or cartridge housing positions, a pressure cam 402 for fixedly holding the cartridges 300 in the playback positions and the like, rewind drive units 500, tape playback units 600 including takeup reel means 700, takeup reel positioning means 800, tape clamping means 900, tape-end sensing means 1000 and capstan drive means 1100, and cases 1200 for storing the cartridges 300 after played.

With reference to the drawings a description will hereinafter be given first of general operations of the apparatus of this invention. In the lift unit 100 positioned at substantially the center of the front of the rack 1 a pair of lift chains 102L and 102R having a plurality of lift guides 101L and 101R are endlessly trained about upper and lower sprockets 103L and 103R, 103R and 103L respectively therebetween in such a manner that the cartridges 300 are each carried by one pair of the lift guides 101L and 101R, and these lift chains are driven by a lift motor 201 depicted in Figures 3 and 4, which are cross-sectional views taken along the lines III-III and IV-IV in Figure 2. To perform this, the shaft of the lift motor 201 has affixed thereto a worm 202, with which a worm gear 203 affixed to a shaft 204 is ganged, and bevel gears 205L and 205R mounted on both ends of the shaft 204 are engaged with bevel gears 105L and 105R, each affixed to one end of each of the shafts 104L and 104R of the sprockets 103L and 103R, by which turning force of the motor 201 is transmitted to the lift chains 102L and 102R to drive them in such a manner as to move the lift guides 101L and 101R pitch by pitch. Accordingly, the lowermost cartridge 300 comes down from the lift guides 101L and 101R onto the cartridge transfer unit 400, as shown in Figures 3 and 4. The cartridge transfer unit 400 consists of a shifting support 403 and a feed member 404, on which the cartridge 300 is supported, as shown. Reference numeral 206 in Figures 3 and 5 designates fixtures for the lift motor 201.

The feed member 404 supporting the cartridge 300 disengaged from the lift guides 101L and 101R is shaped substantially in the form of an L, which is connected to a crank motor 405, fixed to the stationary part, through a crank 406 affixed to the shaft of the crank motor 405 and a rod 407 connected with the crank 406, as illustrated in Figures 3 and 4. The rod 407 is fastened to the feed member 404 through an aperture

bored in a guide member 408. Reference numeral 409 in Figure 4 indicates a plate spring. The rod 407 is guided in a direction indicated by an arrow A or B in Figure 5 in accordance with the forward or backward rotation of the crank motor 405. As illustrated in Figures 2 and 4, the shifting support 403 supporting one part of the cartridge 300 is coupled with a transfer member 412, which is, in turn, mounted on a rotary shaft 411 extending between bearings 410L and 410R. The transfer member 412 has formed therein a concave portion 413, through which the rotary shaft 411 is passed. A gear 414 is affixed to the rotary shaft 411 at the location corresponding to the concave portion 413, which gear is adapted to rotate with the rotary shaft by means of a key 415 formed on the rotary shaft 411 in its lengthwise direction. The gear 414 is also designed to be movable on the rotary shaft 411. Reference numeral 401 identifies a screw rod for driving the transfer member 412, which is coextensive with the rotary shaft 411 in substantially parallel relation thereto and is supported at both ends by the bearings 410L and 410R. The screw rod 401 is threadably engaged with a female screw 417 formed in the transfer member 412 at its lower portion. Accordingly, rotation of the screw rod 401 causes the rotary shaft 411 to serve as a guide rod along which the transfer member 412 is driven to the right or left in Figures 2 and 4. In Figure 4 reference numeral 418 indicates a motor for driving the screw rod 401, and a pulley 420 mounted on the screw rod 401 and a motor pulley 421 mounted on the motor shaft are interconnected by power transmitting means 419 such, for example, as a belt. Reference numeral 422 designates a drive motor for the rotary shaft 411, and a pulley 424 mounted on the rotary shaft 411 and a pulley 425 affixed to the shaft of the motor 422 are similarly interconnected by power transmitting means 423 such as a belt or the like.

Further, the transfer member 412 has passed therethrough a rack 426 in a vertical direction, which is engaged with the aforementioned gear 414 through an intermediate gear 427, if necessary. While, a plate 430 is mounted on an arm 429 normally extending in a horizontal direction in Figure 5 and having formed therein a slot 428 in its lengthwise direction. The arm 429 is attached at one end to the top of the rack 426 by a pin 431 rotatably thereabout and a pin 432 planted on a projecting end formed on the transfer member 412 is engaged with the slot 428 formed in the arm 429. With the above arrangement, rotation of the rotary shaft 411 by the drive motor 422 leads to upward movement of the rack 426 to turn the arm 429 about the pin 431 in a clockwise direction, with the result that the plate 430 held in the horizontal direction, as shown in Figure 5, is brought down in a vertical direction, as depicted in Figure 6. Further, the plate 430 has mounted on its rear marginal portion a substantially L-shaped holder 433 for holding the cartridge 300 at its rear portion in cooperation with the plate 430, and the free end of the holder 433 has formed thereon a projection 434 engageable with a groove 302 (refer to Figure 5) formed in the upper lid 301 of the cartridge 300. The forward end portion of the projection 434 is tapered as at 435 to facilitate engagement with the groove 302 when the rear marginal portion of the cartridge 300 is inserted between the holder 433 and the plate 430 after sliding on the plate 430 and the feed member 404 by pushing the cartridge 300 with the crank motor 405, as indicated by the arrow A. Therefore, the cartridge 300 is placed on the lift guides 101L and 101R so that the groove 302 formed in the upper lid 301 of the cartridge 300 may be at right angles to the direction A in which the cartridge 300 is pushed.

The cartridge 300 transferred onto the shifting support 403 and the feed member 404 is thus inserted between the plate 430 and the holder 433 by the pushing force of the feed member 404 resulting from the rotation of the crank motor 405. After this, the crank motor 405 stops and the cartridge 300 is brought down in a vertical position by the rotation of the motor 422 as depicted in Figure 6 and then the motor 422 stops. After or during this operation the cartridge 300 is

brought to a position opposite to the tape playback unit 600 and is placed on a support plate 436 by the rotation of the motor 418 and accordingly the screw rod 401. In the example shown in Figure 2 two tape playback units 600 and support plates 436 are provided on both sides of the cartridge housing case 1200, but it is of course possible to leave out either one of them. Since they are identical in construction with each other, they are designated by the same reference numerals and the following description will be given in connection with one of them. The support plate 436 is of substantially L-shaped configuration and is provided rotatably about a pin 437 in opposing relation to the front of the panel 601 of the tape playback unit 600, as illustrated in Figures 7 and 8. Opposite the support plate 436 an L-shaped metal member 601 is planted on the panel 601 and a stopper 604 is rotatably attached to the top of the L-shaped metal member 602 by means of a pin 603, as clearly shown in Figure 8. The stopper 604 is biased by a spring 606 so that one end 604a of the stopper 604 normally projects out into the path of the cartridge 300 carried by the shifting support 403 while the other end 604b being engaged with one side of an aperture 605 formed in, for example, the panel 601. When the cartridge 300 is brought on to the support plate 436 the stopper 604 is pushed by the cartridge 300 to turn against the spring 606 and is biased at a position indicated by the broken line in FIG. 8, and when the cartridge 300 has been completely placed on the support plate 436 the stopper 604 is returned to its initial position shown by the full line in the figure. Thereafter, when the support plate 436 is returned to its initial position depicted in Figure 4 by the reverse rotation of the screw rod 401, the projection 434 of the holder 433 is moved along the groove 302 of the cartridge 300 and is easily disengaged therefrom due to the engagement of the cartridge 300 with the free end 604a of the stopper 604.

The support plate 436 is brought to the playback position after the disengagement of the support plate 436 from the cartridge 300. This is accomplished by means of a cam motor 439 and a cam 440 mounted on shaft 438 disposed in substantially the same direction as the pin 437 of the support plate 436 (refer to Figures 1 and 4), as is apparent from Figures 7, 9 and 10, the cam 440 having first to fourth cam faces 440a to 440d. The third cam face 440c holds the support plate 436 at substantially the same as that of the cartridge carried by the shifting support 403, as shown in FIG. 7, and the first cam face 440a holds the cartridge 300 at an angle (substantially vertically in the illustrated example) suitable for playback, as illustrated in FIG. 9.

In the position depicted in FIG. 9 the left-hand end of the upper lid of the cartridge 300 (the upper end of the right-hand side in the figure) engages with a stopper 607 which is secured to the panel 601 and is preferred to be formed of a resilient material. Substantially the central portion of the lid of the cartridge 300 is designed so that one side of a reel 304 housed in the cartridge may abut against an abutment member 502 affixed to the rotary shaft of a rewinding motor 501 mounted on the panel 601.

Referring now to Figure 12, a description will be given of the manner in which the reel 304 is housed in the cartridge 300. As illustrated in the figure, the cartridge 300 is an assembly of upper and lower lids 301 and 305, and a rotary shaft 307 is mounted on the lower lid 305 at substantially the center thereof through a bearing 306, and a reel deck 318 is affixed to the rotary shaft 307. The periphery of the reel deck 318 has attached thereto a spring 308 formed of, for example, a resilient rubber, a pressure spring or the like. Further, the upper lid 301 has an aperture 309 disposed centrally thereof, around which a brake shoe 310 is fixed. The reel 304 housed in the cartridge 300 is normally pressed against the brake shoe 310 by the spring 308 to be prevented from rotation. Reference numeral 311 indicates an aperture disposed centrally of the reel 304 and 312 an aperture formed in the boss or spool of the reel 304. When the reel 304 has been placed on the reel deck of the tape recorder, the aperture 312 engages with a pin projecting out of the reel deck 318 to permit rota-

tion of the reel 304 together with the reel deck 318. As illustrated in FIG. 13, the cartridge 300 has a recess 313 formed at the center of one side thereof and a pair of guide members 314 such as guide rollers are planted on the cartridge 300 on both sides of the recess 313. The tape end is guided by the guide members 314 to pass through the recess 313 and is detachably held at a suitable position in the cartridge 300. Reference numeral 316 designates holding means for this purpose, which means are adapted so that the tape 315 may easily be taken out through the recess 313, as will be described later. In addition, the cartridge 300 has a pair of triangular recesses 317 formed on right and left sides thereof, as depicted in FIG. 13. When the cartridge 300 is held substantially vertical under the condition shown in FIG. 9, one side of the reel 304 is pressed by the face 440a of the cam 440 against the abutment member 502 mounted on the rotary shaft of the rewinding motor 501 to disengage the reel 304 from the brake shoe 310, permitting it to rotate with the reel deck 307.

As is apparent from Figure 12, the abutment member 502 includes an abutment face 503 abutting against one side of the reel 304, a central projection 504 projecting from the abutment face 503 in the extending direction of the rotary shaft of the takeup motor 501 and a projecting member 508 similarly projecting from the abutment face 503 and engaging with an aperture 312 of the reel 304. The projecting member 508 is normally biased to project from the abutment face 503 by means of a spring 507 inserted between the projecting member 508 and a screw 506 screwed into a hole 505 formed in the abutment member 502 from the opposite side from the abutment face 503. Under the above-described conditions shown in FIG. 12, the projecting member 508 and the central projection 504 are respectively engaged with the apertures 312 and 311 of the reel 304 so that the reel 304 may be driven by the rewinding motor 501.

In Figures 12 and 13 the rewinding of the tape 315 is effected at substantially the center of the cartridge 300, but the rewinding can be, of course, accomplished in the manner of the so-called rim driving, as illustrated in FIGS. 14 to 19.

Referring now to FIGS. 14 and 15, a detailed description will be given of the rewinding of the tape. The similar elements to those in FIGS. 12 and 13 are identified at similar reference numerals. The cartridge 300 consists of the upper and lower lids 301 and 305 which are assembled together by means of a hinge 333. The reel 304 having wound thereon the tape 315 is enclosed in the cartridge 300, as clearly depicted in FIG. 15. A fixed shaft 319 is planted at the center of the lower lid 305 of the cartridge 300 and a flange 320 is formed at the base of the fixed shaft 319. Further, a sleeve 322 having a flange 321 extending outwardly from the lower end face thereof is loosely mounted on the fixed shaft 319, with the flange 321 being rested on the flange 320, so that the sleeve 322 may rotate on the fixed shaft 319. The sleeve 322 has screw threads 323 formed on the periphery of the upper end portion thereof. In this case the fixed shaft 319 slightly extends upwards of the sleeve 322 and a flanged box nut 324 is provided to prevent the sleeve 322 from slipping out of its position upwardly. Under such conditions the reel 304 with the tape 315 wound thereon is mounted on the sleeve 322 mounted on the fixed shaft 319. In this case the underface of the reel 304 around the central aperture 311 thereof rests on the flange 321 of the sleeve 322. In the underface of the reel 304 inside of the spool 325 thereof a groove 326 is formed contiguous to, for example, the central aperture 311 and an engaging piece 327 is planted on the flange 321. Mounting the reel 304 on the sleeve 322, the engaging piece 327 is engaged with the groove 326, so that the reel 304 can rotate with the sleeve 322. While, a tubular cap 329 having screw threads 328 formed on the inside thereof is threadably engaged with the screw threads 323 of the sleeve 322 and the lower end face or a flange 330 of the cap 329 presses down the reel 304 through a resilient piece 331. Thus, the reel 304 is adapted to be rotatable with the sleeve 322 without causing play in the axial direction thereof. Further, the tape 315 in the cartridge 300 is taken out

therefrom through the recess 313 and the reel 304 is adapted to be driven through a rotor 509. Reference numeral 332 designates a recess which is formed in the cartridge 300 for this purpose and is designed so that at least a pair of flanges 304a and 304b of the reel 304 are partially exposed outside. The rotor 509 for driving the reel 304 has formed therein inclined faces, which are urged in driving contact with the rims of the flanges 304a and 304b, or grooves of a width corresponding to the thickness of the flanges 304a and 304b. Further, these inclined faces or grooves are formed of a resilient material such as rubber and the rotor 509 is pushed in the direction of the axis of the reel 304 into driving contact with the flanges 304a and 304b of the reel 304, to drive it in the so-called rim drive manner. In this case play of the reel 304 due to the pressing by the rotor 509 and a resonance phenomenon attendant upon the rotation of the reel 304 are prevented as described hereinbelow. For this purpose, the rotor 509 is constructed, as shown in FIGS. 19A and 19B, which has formed thereon inwardly inclined faces 509a and 509b or outwardly inclined faces 509a' and 509b' for engagement with the rims of the flanges 304a and 304b of the reel 304. Otherwise, grooves 509a'' and 509b'' of a width corresponding to the thickness of the flanges 304a and 304b of the reel 304 are formed in the rotor 509, as illustrated in FIG. 19C.

Referring now to FIGS. 16 to 18, a description will be given of means for enabling the user to confirm whether the tape 315 is loaded in the cartridge 300 or not and means for permitting the rotor 509 to get in driving contact with reels of different diameters substantially at a predetermined position to minimize the influence of the size of the reels on back tension rendered to the tape, ensuring substantially uniform rewinding of the tape. FIG. 16 illustrates three cartridges 300 of this invention placed side-by-side, and FIG. 17 is a plan view of the cartridge 300 depicted in FIG. 16, with the right-hand cover removed. FIG. 18 is a schematic diagram illustrating the relative positions of a rotor, the fulcrum of an arm rod, a reel and a brake pad in FIG. 17. In these figures similar elements to those of the above-described cartridge are marked with similar reference numerals and no description will be made in connection therewith. The cartridge 300 is a shallow case of a square configuration. The front wall of the cartridge 300 has a window 334 formed by punching or formed of a transparent material. It is preferred that a handle 335 is provided above the window 334 for facilitating the handling of the cartridge 300. Reference numeral 304 designates a tape reel of large radius, which is pivotally mounted on a pin 338a provided at one free end of an arm lever 337 which is, in turn, pivoted on a pin 336 located at an upper right-hand corner of a lower cover 305 of the cartridge 300. On the other free end of the arm lever 337 there is provided a male screw 339 for fixing within the cartridge 300 the arm lever 337 selectively at a specific position in accordance with the size of the reels employed. The male screw 339 is adapted to be screwed into either one of female screws 340 and 341 which are positioned at different locations in the cartridge 300. One end of a tape 315 wound on a tape reel 304 is drawn out toward the lower sidewall of the cartridge 300 and is guided by guide members 314 on the inside of a recess 313 provided for pulling out the tape, thereafter being pressed against a sidewall contiguous to the lower sidewall by holding means 316 consisting of a spring 342 and a pad 343 provided at one end thereof. In case of playing the tape 315 is pulled out from the recess 313 and is guided to a magnetic head assembly (not shown). The window 334 is provided for viewing the inside of the cartridge 300 to see if the tape end is held in position. Further, a guide roller 344 is provided on the sidewall of the cartridge 300 at the location where the tape end is pressed against the sidewall. This facilitates the pressing of the tape end against the sidewall and pulling back the tape end when the tape 315 is pulled out from the recess 313.

The cartridge 300 has a recess 332 of a circular arc configuration, as mentioned previously, through which a rotor 509

makes rotary contact with the rim of the reel 304. The rotor 509 drives the reel 304 when rewinding the tape 315 and yields back tension when the tape 315 is drawn out from the cartridge 300.

- 5 This invention is to provide a specific construction which is usable with a reel 304 of a large diameter such, for example, as 10 inches and a reel 345 of a small diameter such as, for example, 3 inches, and in which either one of the reels is selectively mounted on the reel mounting shaft 338a of the arm lever 337. A brake 346 is located at a position substantially symmetrical with the rotary contact point between the reel 304 and the rotor 509 with respect to a line L-L' joining the shafts 338a and 338b of the reels 304 and 345, and the brake 346 is adapted to make contact with the rim of the reel 304. The brake 346 consists of a brake shoe 347 made up of felt or the like and contacting the reel 304, an arm 348 holding the brake shoe 347 and a spring 349 acting upon the arm 348. Reference numeral 510 designates a rod having the rotor 509 pivotally mounted on one end thereof, which rod is pivoted by a pin 511 to a stationary part in a rotatable manner. The other end of the rod 510 is mounted on one end of a rod 512 in such a manner as to move along the rod 512, and a spring 513 is mounted on the rod 512, as illustrated, so that when the rod 512 is pulled to the right the rotor 509 is brought into resilient contact with the reel 304 or 345.

When the reel 345 of small radius is mounted on the shaft 338a of the arm lever 337 in place of the reel 304 of large radius, the male screw 339 provided on the arm lever 337 remote from the shaft 338a is unscrewed from the female screw 340 and is then screwed into a female screw 341. In this case, the arm lever 337 and the reel 345 assume positions indicated by chain lines. In the present invention the reel 345 gets into rotating contact with the rotor 509 at such a position 35 that the arm lever 337 has turned through some angles about the shaft 338. It is preferred in practice that such a position approaches as much as possible the position where the reel 304 of large radius makes rotating contact with the rotor 509. For this purpose, the dimensions of the respective members 40 are selected so that the center O of the rotor 509 lies substantially on a bisector of an angle defined by a line joining the center 338a of the reel 304 with a point P where the reel 304 makes contact with the rotor 509 and a line joining the center 338b of the reel 345 with a point P. In such a case, the points P 45 a little deviate from the lines joining the centers 338a and 338b of the reels 304 and 345 with the center O of the rotor 509, but such deviations are substantially the same with the both reels. Hence, it may be said that the action of the rotor 509 upon the reels is substantially similar.

50 In the apparatus described above, the rotor 509 is urged into rotating contact with the reel with the brake 346 being held off to lead the tape 315 to the recording and reproducing device through the recess 313 while applying back tension to the reel. For rewinding of the tape a drive roller is coupled with the rotor 509 to drive the reel to take up thereon the tape. After taking up the tape 315 on the reel, the tape end is drawn out from the reel to be led to the holding means 55 through the guide rollers 314 and 344, and the tape end is held between the pad of the holding means and the sidewall of the cartridge 300 by the spring 342 retained at its initial position, as mentioned previously. When using the tape reel of small diameter, the arm lever 337 is turned and the male screw 339 is screwed into the female screw 341. The operation in this 60 case is the same as that in the foregoing. As illustrated in FIG. 18, the both reels make rotating contact with an idler at substantially predetermined positions.

65 The brake 346 is provided for preventing the rotation of the reel while handling the cartridge 300. In the illustrated example the brake 346 is designed so that its brake pad 347 engages with the reels at the same position, but this is not always necessary.

70 While the present invention has been described in connection with the case where two different reels are employed, the present invention can similarly be applied to the case where

more than three different reels are used. That is, it is sufficient for the purpose only to construct and selectively fix the arm lever in such a manner that the conditions of the rotating contact of the reels with the rotor are substantially the same.

In accordance with the present invention the cartridge device can readily be used with different types of reels under substantially the same conditions. Further, in the case of employing a cartridge made of an opaque material, prior to drawing out the tape from the reel through the recess 313, it can readily be known whether the tape is wound on the reel by confirming it through the window 334 if the tape end is pressed against the inside wall of the cartridge by the holding means 316. The tape is usually brown, so that if the pad 343 is colored, for example, green, it can readily be known that the tape is not wound on the reel when the green color is seen through the window. In this case it is possible to discriminate the tapes by providing various colored portions or marks on the tape ends according to their kinds.

As has been described in the foregoing, since the tape end can easily be seen through the window 334 formed through the front wall with the handle 335 mounted thereon when the tape loaded in any of the cartridges arranged one on another is drawn out through the recess 313 for playback, it can be confirmed whether the tape is loaded in the cartridge without taking off the upper lid thereof. Further, the cartridge of this invention can be used with conventional types of reels such, for example, as those of 5, 7 and 10 inches in diameter and specific ones, although some of them necessitate the use of adapters.

In this case, there is no need of employing any specific tape and presently available ones can be used, and further no special treatment on the tape end is required. While transporting the cartridge with the tape encased therein, the tape reel is normally clamped, and only during playing the reel is taken off from the brake. This simplifies clamping of the tape end portion.

With the cartridge having enclosed therein the reel described above, rewinding operation of the tape can be accomplished in various modes such as driving of the reel at its center, the so-called rim drive and so on, and accordingly the tape cartridge is suitable for use in automatic playing.

The foregoing description has been given, by way of example, in connection with the manner in which cartridges 300 arranged one on another are automatically brought to the playback position one after another, and the construction of the cartridge has been described in detail. Now, a description will be given of the tape playback unit 600. FIG. 20 is an enlarged schematic diagram of one portion of the tape playback unit 600 depicted in FIG. 2. In the figure reference numeral 700 designates a takeup reel disposed on the panel 601 at a predetermined position. As shown in FIGS. 21 and 22, the takeup reel 700 has a pair of flanges 700a and 700b. The lower flange 700a has on its center axis a shaft 701 extending downward, which shaft is coupled with a rotary shaft of a takeup motor 702. The upper flange 700b consists of two sectoral plates 704 and 705 which are arranged concentrically with the lower flange 700a and substantially symmetrically with respect to a straight line 703 passing the axis of the flange 700b in a radial direction. Reference numeral 706 indicates a central aperture of the flange 700b. The flanges 700a and 700b are formed integral with each other in a manner to provide a bobbin 707 therebetween except at places corresponding to the discontinuous portions defined by the sectoral plates 704 and 705. That is, the bobbin 707 is formed except a predetermined angular range about the line 703. Further, pins 708 and 709 are planted on the flange 700a at such positions as are point-symmetrical with each other relative to the axis of the flange within a space surrounded by the bobbin 707. The pins 708 and 709 have pivoted thereto tape clamp pieces 710 and 711. The clamp pieces 710 and 711 are shaped in an arcuate configuration and are disposed with the peaks of their bent portions opposed to each other, as illustrated in FIG. 21. In addition, these clamp pieces 710 and 711 are respectively

biased by springs 712 and 713 normally to be urged into resilient contact with each other at the axis of the takeup reel 700. The shaft 701 has mounted thereon a cam plate 801 having a pair of parallel faces, crossing the line 703 at right angles thereto.

Reference numeral 602 indicates a magnetic head and 1101 and 1102 capstans disposed on the right and left sides of the magnetic head 602 in the tape path, as illustrated. Reference numerals 603 and 604 designate pinch rollers which are respectively urged into rotating contact with the capstans 1101 and 1102, with the tape 315 being gripped therebetween thereby to drive it. In this case the capstan 1101 is adapted to be a main capstan of large torque, and when it is rotated in a direction to drive the tape 315 at a constant speed to the takeup reel 700 the other capstan 1102 is rotated by a small torque in a reverse direction to apply a predetermined tension to the tape 315 at the position of the magnetic head 602. Otherwise, the both capstans are driven in the same direction, in which case the capstan 1102 is used as a main capstan and the peripheral speed of the capstan 1102 is a little increased, as compared with that of the capstan 1101, to provide the tape 315 with a predetermined tension. This will be described in detail later on.

25 The magnetic head 602, the capstans 1101 and 1102 and the pinch rollers 603 and 604 are positioned relative to one another in the following manner. On the basis of the position of the tape drawn out from the cartridge 300, namely the line 703 joining the position of the recess 313 and the axis of the 30 takeup reel 700, the magnetic head 602 and the capstans 1101 and 1102 are normally disposed on the left of the line 703, while the pinch rollers 603 and 604 are positioned on the right side of the line 703, as illustrated in FIG. 20.

35 Reference numerals 605 and 606 identify tension levers, which are respectively pivoted to pins 607 and 608 provided on the left of the magnetic head 602. The free ends of the tension levers 605 and 606 have secured thereto engaging members 609 and 610 of a roller or pin construction and are normally positioned on the right side of the line 703 and the upper 40 and lower sides of the capstans 1102 and 1101. The tension levers 605 and 606 have associated therewith engaging pieces 611 and 612 such as will be described later.

45 Reference numeral 613 designates a front cover for shielding the magnetic head 602, which cover is normally positioned on the right side of the line 703 and is coupled with a shifter rod 614 in such a manner as to be shifted to the left. The shifter rod 614 has at one free end engaging members 615 and 616 engaging with the engaging pieces 611 and 612 of the tension levers 605 and 606. The other free end portion of the 50 shifter rod 614 has provided thereon, for example, a rack 617 adapted to mesh with a gear 618. The gear 618 is coupled with a shifter drive motor 619 by means of a belt or a chain.

55 Further, a rod 802, which engages with the aforementioned cam 801 of the takeup reel 700, is provided in a manner to be movable to the right and left. The rod 802 has formed thereon at one free end portion a rack 803 with which a gear 804 meshes. The gear 804 is similarly connected with the motor 619 by means of a belt or chain.

60 With such an arrangement as described above, the front cover 613 is brought to the position of the magnetic head 602 through the rod 614 by the drive of the motor 619, and the tension levers 605 and 606 render a predetermined tension to the tape 315 to urge it into contact with the magnetic head 602. While, when the takeup reel 700 has been brought by the 65 rod 802 to a predetermined rotational angular position, namely to a position in alignment with the line 703, the rod 802 is disengaged from the cam 801.

70 Reference numeral 1011 indicates a rotary arm having planted thereon at one free end a tape engaging member 1011a such as a pin, a rotor or the like, and a plunger 1007 is associated with the rotary arm 1011. The rotary arm 1011 is coupled with another rotary arm 1001 by means of a resilient belt 1011b. The rotary arm 1001 is adapted so that its free end 75 may be inserted between the opposed flanges 700a and 700b

of the takeup reel 700, and the free end has mounted thereon contacts. When the contacts get in abutment with the bobbin 707 of the reel 700, they are closed due to conductivity of the bobbin 707 itself or a conductive member previously provided on the bobbin 707, indicating that the tape on the takeup reel 700 has been entirely drawn out therefrom. By the closing of the contacts an electrical circuit is controlled for performing subsequent operations. Accordingly, the plunger 1007 is not normally energized so that the engaging member 1011a of the rotary arm 1011 lies on the left side of the line 703, and when the tape 315 is rewound from the takeup reel 700 the plunger 1007 is energized to move the engaging member 1011a to the right. In this case, the engaging member 1011a and a guide member 620 provided above the magnetic head 602 are positioned relative to each other in such a manner that the tape 315 does not lie at least on the magnetic head 602 when the tape is stretched in a straight line in contact with the engaging member 1011a and the guide member 620 in the case where the plunger 1007 has been energized to have pushed to engaging member 1011a to the right. In the figure the tape does not lie on the capstans 1101 and 1102. Further, a screw rod 621 is disposed between the takeup reel 700 and the cartridge 300 substantially in parallel with the line 703 and a shifting member 622 is attached to the screw rod 621, on the free end of which a tape clamer 900 is mounted. Reference numeral 623 designates a guide rod for the shifting member 622 extending in parallel with the screw rod 621. The screw rod 621 is coupled with a motor 624 by means of a pulley, a belt and so on.

The playback unit 600 has such a construction as described above. A detailed description will hereinbelow be given in connection with the reel, reel positioning means, the tape clamer and so on employed in the playback unit 600.

The takeup reel 700 exemplified in FIGS. 21 and 22 may be substituted with those illustrated in FIGS. 23 to 26, in which similar elements to those in FIGS. 21 and 22 are identified by the similar reference numerals, and no detailed description will be given thereon. That is, a pair of pins 708 and 709 are planted on the lower flange 700a of the takeup reel 700 within its central aperture 706. The pins 708 and 709 are planted in parallel with the shaft 701, which have an angle θ with the line 703 and are located at positions dot-symmetrical relative to the shaft 701 on both sides of a line A'-A' passing the center axis O of the reel 700 and extending between the two sectoral plates 704 and 705 of the upper flange 700b. Further, clamp pieces 710 and 711 are similarly pivoted on the pins 708 and 709 at places dot-symmetrical relative to the shaft 701. In this case, the clamp pieces 710 and 711 are bent outwardly at one end, as indicated by 712 and 713, and they are pivoted at the respective ends of their bent portions on the pins 708 and 709. On either clamp piece, a pair of pins 714a and 714a' or 714b and 714b' are provided which have rotatably mounted thereon a pair of rollers 715a and 715a' or 715b and 715b' which are in meshing or rotary contact with each other. The clamp pieces 710 and 711 are respectively associated with press springs 716a and 716b and are thereby biased in a clockwise direction in the figure so that the rollers 715a and 715a' are in resiliently meshing or rotary contact with the rollers 715b and 715b' on the line A-A'.

It is preferred to provide the clamp pieces 710 and 711 with means for limiting their rotational angular range, (namely rotational movement). The limiting means may be provided in the form of projections 717 and 718, which are planted on the free ends of the clamp pieces 710 and 711 and are engaged with arc-shaped apertures 719 and 720 formed through the flange 700a. Thus, the rotational angular range of the clamp pieces 710 and 711 can be limited by selecting the arc length of the arc-shaped apertures 719 and 720. The rollers 715a, 715a', 715b and 715b' may take the form of rollers having knurled peripheral surfaces or elastic rubber rollers which get in frictionally rotating contact with one another.

In order to take up the tape 315 on the takeup reel 700, the reel 700 is rotated in a direction against the biasing forces of

the springs 716a and 716b of the clamp pieces 710 and 711, namely in a counterclockwise direction, as indicated by an arrow a in FIG. 23. At the same time, the clamp pieces 710 and 711 are respectively spread out in the counterclockwise direction against the biasing forces of the springs 716a and 716b, and then one end 315a of the tape 315 is inserted and gripped between the rollers 715a and 715b and between 715a' and 715b' of the clamp pieces 710 and 711. Under such conditions the reel 700 is rotated in the counterclockwise direction. Thus, at the start of the winding of the tape on the bobbin 707 a force is rendered to one clamp piece 710 by the tape 315 but this force is applied to the piece 710 in the vicinity of its fulcrum, namely the pin 708, and consequently the clamp piece 710 hardly rotates to ensure that the tape end portion 315a is held in position between the rollers 715a and 715b and between 715a' and 715b'.

Let it be assumed that the tape 315 is pulled in a direction as indicated by Z, to slip out of position between the rollers 715a and 715b and between 715a' and 715b', as illustrated in FIG. 26. In such a case, the rollers, for example, 715a and 715b, are caused to rotate in directions indicated by arrows by the pulling force of the tape 315, but since the rollers 715a and 715b are in meshing or rotating contact with the rollers 715a' and 715b' respectively, the rollers 715a' and 715b' are thereby rotated in a direction to pull in the tape 315 therebetween, namely in a direction opposite to the arrow Z. In this manner, the tape end portion 315a is not pulled out of position between the rollers 715a and 715b and between 715a' and 715b' and is held in position therebetween.

Then, a description will be given in connection with the case where the tape 315 is drawn out from the takeup reel 700 by rewinding. In this case the takeup reel 700 is rotated in a clockwise direction as indicated by an arrow a', as illustrated in FIG. 25 and accordingly when the tape 315 has been entirely paid out from the reel 700 at least one clamp piece 710 is pulled by the tape 315 against the spring 716a in the counterclockwise direction. The point of application of the force exerted upon the clamp piece 710 by the tape 315 is fully spaced from the pin 708 planted on the free end of the clamp piece 710 which serves as the fulcrum of its rotational movement. Accordingly, the clamp piece 710 effectively turns on the pin 708 against the spring 716a to disengage the rollers 715a and 715a' of the clamp piece 710 from those 715b and 715b' of the other clamp piece 711, with the result that the tape end portion 315a is easily pulled out from between the rollers 715a and 715b and between 715a' and 715b'.

As has been described in the foregoing, the particular construction of this invention facilitates and ensures engagement and disengagement of the tape 315 with or from the takeup reel 700, and hence is of particular utility when employed in a magnetic recording and reproducing device for an automatic player.

In FIG. 27 there is illustrated another example of the reel positioning means, which performs the same function as that of the adjusting means 800 exemplified in FIGS. 20 to 22 but in which a cam is coupled with the rod 802 depicted in FIG. 20 and the face of the cam 801 mounted on the reel shaft 701 in FIG. 20, is shaped in such a configuration as permits its engagement with the newly provided cam.

Assume that the takeup reel 700 is placed in such a position that its clamp pieces 710a and 710b lie opposite to each other across the line 703 at locations where the line A and the line 703 overlap each other, as depicted in FIG. 27. Under such conditions, the clamer 900 lying above the takeup reel 700 is brought to the cartridge 300 by rotation of the screw rod 621 passing over the reel 700 and clamps or picks up the tape 315 projecting in the recess 313, thereafter being brought back to the takeup reel 700. Then, the clamer 900 spreads out the opposed clamp pieces 710a and 710b and draws the tape 315 therebetween, and releases the tape 315 after having passed the clamp pieces 710a and 710b, thus holding the tape 315 therebetween. Following this, the clamer 900 is brought to a position independent of the rotational movement of the

takeup reel 700. Accordingly, when the end portion 315a of the tape wound on the cartridge 300 has been engaged with the takeup reel 700, the pinch roller 604 is urged into rotating contact with the capstan 1101 and the takeup reel 700 is driven, by which the tape 315 is taken up on the takeup reel 700 while being drawn across the magnetic head 602. In this manner, automatic winding of the tape is accomplished.

With the above arrangement, the takeup reel 700 must be always put in the illustrated condition that the lines A and 703 overlap each other as depicted. The reel positioning means for the takeup reel 700 will hereinbelow be described in detail with reference to FIGS. 28 and 29, in which similar elements to the aforementioned ones are identified by similar reference numerals and no detailed description will be given in connection therewith. As depicted in FIGS. 28 and 29, the rotary shaft 701 of the takeup reel 700 has mounted thereon a cam 801 having a pair of cam faces 801a and 801b which are symmetrical relative to a line Y-Y passing the shaft 701. While, a shaft 805 pivoted on a base plate (not shown) has mounted thereon a drive cam 807 having a cam face 806 for engagement with the cam faces 801a and 801b of the cam 801. The drive cam 807 is rotated from the outside to turn the cam 801 and the rotary shaft 701, by which the takeup reel 700 is brought to such a position that the line A overlaps the line 703. In this case the cam face 806 of the drive cam 807 has an arc-shaped face about its rotary shaft 805 and the cam faces 801a and 801b of the cam 801 have concave faces of the same curvature as that of the arc-shaped cam face 807. Further, both end faces of the cam faces 801a and 801b of the cam 801 provide cam faces 808a and 808b, 808c and 808d extending in the axial direction on the line Y-Y.

Consequently, when the cam 801 is at a rotational position such as shown in FIGS. 30A or 30B, one end of the cam face 806 of the drive cam 807 engages with the cam face 808c (or 808b) or 808d (or 808a) of the cam 801 to turn the cam 801, with the result that the cam face 801a or 801b of the cam 801 snugly engages with the cam face 806 of the drive cam 807. Under such conditions, even if the drive cam 807 turns, the cam 801 rotates no more but assumes a position shown in FIG. 28 where the line Y-Y crosses the line A at right angles thereto. Thus, the cam 801 is brought to a position where the line A overlaps the line 703.

In the foregoing there is a possibility that when the cam 801 assumes a position illustrated in FIG. 30C such that either one of top ends 809a and 809b of the cam 801 engages with one end of the drive cam 807, smooth rotational movement of the cam 801 may be inhibited by the relation of the line of action of the drive cam 807 to the cam 801. To avoid this, a rotary disc 810 is mounted on the rotary shaft 701 integrally with or separately from the cam 801, on which disc is planted a pair of pins 810a and 810b symmetrically with respect to the shaft 701. While, an engaging member 811 is attached to the cam 807, and when the top end 809a or 809b of the cam 801 is about to get in contact with one end of the drive cam 807 the engaging member 811 engages with the pin 810a or 810b prior to the engagement of the cam 801 with the drive cam 807, thereby slightly turning the rotary shaft 701 and consequently the cam 801. That is, the cam 801 is shifted from the position of full line to that indicated by a broken line, as illustrated in FIG. 30C.

As is apparent from the foregoing, with the above construction, the takeup reel 700 can automatically be brought to the automatic playback position and the positioning of the reel 700 can be effected by a very simple construction with high accuracy.

Although the above construction has been described in connection with the control of the positioning of the specific takeup reel 700 described with FIG. 27, it can be applied to the positioning of the takeup reel for the purpose of bringing the starting or terminating end of the tape to a specific position. Accordingly, reference to the above-described takeup reel 700 should not be construed as limiting this invention specifically thereto.

Referring now to FIGS. 31 to 35, the tape clamer 900 will hereinbelow be described in detail. FIG. 31 is a schematic diagram for explaining the tape clamer 900. The shifting member 622 is moved along the guide rod 623 by rotation of the screw rod 621 arranged in parallel with a line joining the cartridge 300 and the takeup reel 700. The clamer 900 carried by the shifting member 622 picks up the tape 315 in the cartridge 300 and brings it to the takeup reel 700 to be wound thereon. As exemplified in FIGS. 31 to 33, the shifting member 622 is provided with an arm 901 extending downward and another arm 902 extending substantially at right angles to the arm 901. On the free end of the arm 901, there is provided a fixed clamping piece 904 which extends at right angles to the arm 901, namely in the same direction as that of the arm 902, and has at its free end a tape holding member 903 formed in its lengthwise direction. Further, a bearing portion 905 is provided on the free end of the arm 901 in opposed relation to the arm 902 and a rotary shaft 906 is provided between the bearing portion 905 and the arm 902. On the rotary shaft 906 on the free end of the arm 901 there is mounted a rotary clamping piece 907 in opposed relation to the fixed clamping piece 904, which piece 907 clamps the tape 315 in cooperation with the fixed clamping piece 904. The free end of the rotary clamping piece 907 is provided with a tape holding member 908 at a position corresponding to that 903 of the fixed clamping piece 904. In this case, the rotary clamping piece 907 is turned by the rotary shaft 906 to such a position that the foot of a perpendicular, drawn from the free end of the rotary clamping piece 907 to the fixed clamping piece 904, lies at least further to the inside, namely the stationary part than the inner edge of the tape holding member 903 of the fixed clamping piece 904.

A spring 909 is wound on the rotary shaft 906, with one end 35 being fastened thereto and the other end to the arm 901, by which the rotary shaft 906 is biased normally to hold the rotary piece 907 in spaced relation to the fixed piece 904.

The rotary piece 907 is adapted so that when it goes on rotating in a direction opposite from the fixed piece 907 one side of the other free end 910 of the rotary piece 907 abuts with a stopper portion 911 of the arm 901 to prevent further rotational movement of the piece 907.

While, a drive piece 912 is affixed to the free end of the rotary shaft 906 on the side of the shifting member 622. The rotary shaft 906 is turned by the drive piece 912 to bring the tape holding member 908 of the rotary clamping piece 907 into engagement with that 903 of the fixed piece 904.

In this case, the rotary shaft 906 is designed so that the rotary clamping piece 907 can be held at such a position as maintaining the tape holding members 908 and 903 in contact with each other. To this end, a stopper 913 is provided on the free end of the arm 902, which engages with the drive piece 912 at a predetermined rotational position of the rotary shaft 906 and holds the rotary shaft 906 at that rotational position. The stopper 913 may be formed in, for example, an L-shaped configuration and is rotatably pivoted at its bent portion to a pin coextensive with the arm 902.

The stopper 913 is associated with a spring 915 to be supplied with a biasing force tending to turn it in a counter-clockwise direction in Figure 33. It is also possible that the other free end of the stopper 913 is bent to provide a hook portion 916 for engagement with the free end of the drive piece 912. Further, in the illustrated example the top end face 65 of the hook portion 916 is tapered, as indicated by 917, by which, when the drive piece 912 is turned in a clockwise direction by an external force, the free end of the drive piece 912 is moved over the tapered face 917 into engagement with the hook portion 916 while turning the stopper 913 against the biasing force of the spring 915. When the stopper 913 is turned against the spring 915 under the condition that the free end of the drive piece 912 is in engagement with the hook portion 916, the drive piece 912 is disengaged from the hook portion 916 to permit rotation of the drive piece 912 and consequently the rotary shaft 906 by the spring 909. In this case,

the stopper 913 is returned to its initial position by the spring 915 subsequent to the disengagement of the drive piece 912. In addition, it is possible to provide the arm 902 with a stopper face 918 which limits the rotational movement of the stopper 913 by the biasing force of the spring 915.

Further, abutment members 919 and 920 are provided on stationary parts as illustrated in Figure 30. The abutment member 919 abuts with the drive piece 912 and turns it against its rotating biasing force, namely the biasing force of the spring 909 when the clamper 900 has been brought to the cartridge 300. While, the other abutment member 920 abuts with the free end of the stopper 913 on the opposite side from the hook portion 916 and turns the stopper 913 against the biasing force of the spring 915 when the clamper 900 has been brought down in the figure past the takeup reel 700.

With such an arrangement, when the clamper 900 has been brought to the cartridge 300 by rotating the screw rod 621, as previously described with FIG. 20, the tape holding member 903 of the fixed clamping piece 904 is caused to contact with or face close to one side of the tape 315 placed in the cartridge 300 and at the same time the drive piece 912 is urged into abutment with the abutment member 919. Thus, since the drive piece 912 and accordingly the rotary shaft 906 is turned against the biasing force of the spring 909, the tape holding member 908 of the rotary clamping piece 907 is brought into contact with the other side of the tape 315. As a result of this, the tape 315 is held or clamped between the tape holding members 903 and 908. While, in this case the free end of the drive piece 912 has got over the tapered face 917 of the hook portion 916 of the stopper 913 and hence engages with the hook portion 916 and is held at this rotational position. When the clamper 900 having held the tape 315 is brought down to the takeup reel 700 in FIG. 31, the fixed clamping piece 904 forcibly spreads out the opposed clamp pieces 710 and 711 and passes through therebetween to bring the tape 315 in position between the clamp pieces 710 and 711. Thereafter, when the clamper 900 has been further brought down past the reel 700, the free end of the stopper 913 on the opposite side from the hook portion 916 gets into contact with the abutment member 920 and the stopper 913 turned against the spring 915. As a result of this, the drive piece 912 is disengaged from the hook portion 916 to return to its initial position due to the spring 909, so that the end portion of the tape 315 is disengaged from the clamper 900 to be left on the takeup reel 700.

Referring now to FIGS. 34 and 35, a description will be given of a modification of the clamper means. Reference numeral 900 indicates generally a clamper, which includes opposed plates 921 and 922 planted at one end, a fixed plate 924 having at its free end a tape holding member 923, a rotary arm 926 pivoted on a shaft 925 extending between the plates 921 and 922 and a rotary arm 928 similarly pivoted on the shaft 925 and having at its free end a tape holding member 927. The rotary plate 928 has a centrally disposed projection 929 extending in a lateral direction, and the free ends of the projection 929 and the rotary arm 926 are coupled by a common pin 930. An operating rod 932 of an electromagnetic plunger 931 is coupled with the other free end of the rotary arm 926 by means of a shaft 933. Further, a spring 934 is interposed between the stationary part supporting the fixed plate 924 and the pin 930. Reference numeral 935 designates a groove formed in the fixed plate 924 for permitting rotation of the pin 930.

The construction of the tape clamper will hereinbelow be described together with its operations. Assuming that when the plunger 931 is in its inoperative condition its operating rod 932 projects to the right, the free end of the rotary arm 926 and the tape holding member 927 of the rotary plate 928 lie on the left of a line Q joining the shaft 925 and the tape holding member 923 in Figure 35. Accordingly, the tape 315 inserted between the tape holding member 923 and the rotary plate 928 can be seen from the left in Figure 35 without being obstructed by the tape holding member 927. In this case, the line of action of the spring 934 stays on the left of the shaft

925, holding the clamper in its locked condition. Under such conditions, application of a current to the plunger 931 actuates it to pull the operating rod 932 to the left, by which the rotary arm 926 and the rotary plate 928 are turned in the counterclockwise direction to bring the tape holding member 927 into contact with that 923 of the fixed plate 924. In this case, the line of operation of the spring 934 moves to the right of the shaft 925 to ensure that the tape holding members 923 and 927 are held in contact with each other by the spring 934 even after the plunger 931 has been put in its inoperative condition. Disengagement of the tape holding members can be effected only by pushing the shaft 930 to the left.

In order to push the shaft 930 to the left, a fixed member 936 is provided at a position deviated from the center of the takeup reel, as depicted in Figure 31. However, the fixed member 936 must be located in such a position as not to be in the way of the tape clamper 900 when it is brought to the cartridge 300 from its standby position above the takeup reel 700. In compliance with this requirement the fixed member 936 is positioned at such a location that it engages with the shaft 930 when the clamper 900 holds the tape 315 but that it does not engage with the shaft 930 when the clamper 900 does not hold the tape 315, since the shaft 930 lies at different distances from the base plate according as the clamper 900 holds the tape 315 or not. When the tape clamper 900 has been brought up to the position of the cartridge 300 in FIG. 31, the tape holding member 923 can be seen from the left in FIG. 35, as described above. The tape 315 can be brought to the recess 313 of the cartridge 300 within a space through which the tape holding member 923 can be seen. Accordingly, when the tape holding member 923 engages with or stands opposite to the tape 315 the tape holding member 923 stays above the tape 315. Under such conditions the tape clamper 900 comes to a standstill and then the plunger 931 operates to pick up the tape 315.

As has been described above, the tape clamper of this invention is capable of clamping the tape without fail by the employment of a spring and is applicable to an automatic magnetic recording and reproducing apparatus.

Referring to Figures 36 to 38, a description will be made in connection with means for detecting the tape 315.

In automatic recording and playback apparatuses, when a magnetic tape after played back has not been completely rewound on its supply reel and remains left on a takeup reel a subsequent tape cannot be wound on the takeup reel, causing a trouble in the automatic playing operation.

To avoid this, the present invention employs novel tape detecting means by which it is detected whether a tape after played still remains left on the takeup reel before starting play of a subsequent tape and, if rewinding of the preceding tape has not been completed yet, drive of the automatic playing device is stopped. Before describing the tape detecting means a general description will be given of an automatic playing apparatus to which the detecting means can be applied.

In Figure 36 a tape cartridge 300, a takeup reel 700, a pinch roller 604, a capstan 1101, a magnetic head 602, a tape clamper 900, a shifting member 622, a screw rod 621 and a guide rod 623 are the same as those previously described, and hence no description will be given in connection therewith.

In the figure the clamper 900 is brought to the position of the cartridge 300 by driving the screw rod 621 and is then caused to pick up the tape 315 at the position of the recess 313, after which the clamper 900 holding the tape 315 is brought back to the takeup reel 700. Then, the clamper 900 spreads out the opposed clamp pieces 710 and 711 of the takeup reel 700 to lie the tape 315 therebetween and releases the tape after having passed through between the clamp pieces 710 and 711, so that the tape 315 is tightly held in position therebetween, as previously described in this specification. Following this, the clamper 900 is moved out of the range of the rotational movement of the takeup reel 700. Thereafter, the pinch roller 604 is urged into rotating contact with the capstan 1102 and the takeup reel 700 is driven, by which the

tape 315 mounted on the cartridge 300 is automatically wound on the takeup reel 700 across the magnetic head 602 while recording and reproducing.

When the tape 315 has been entirely taken up on the takeup reel 700 to complete its magnetic recording or reproducing, a signal previously recorded, for example, on the tape end portion is picked up by the magnetic head 602, by which the recording or reproducing operation is stopped and the reel in the cartridge 300 is rotated to rewind thereon the tape 315 wound on the takeup reel 700. In this case the clamer 900, the pinch roller 604 and so on are adapted to be retained at their initial position prior to the start of the playing. Upon completion of the rewinding of the tape 315 on the reel of the cartridge 300, the cartridge 300 is automatically replaced with another cartridge for subsequent playing. If, however, the tape is cut during the rewinding operation and remains on the takeup reel 700, a subsequent tape cannot be taken up on the takeup reel 700, with the result that further playing cannot be accomplished and the tape is likely to get entangled and damaged.

To avoid this, the present invention employs tape end detecting means 1000 adapted to detect the presence of the tape on the takeup reel 700 prior to the initiation of subsequent playing and inhibit the playing, if the tape still remains on the takeup reel 700. For this purpose, the entire takeup reel 700 or only its bobbin 707 is formed of a conductive material or at least one selected area of the peripheral surface of the bobbin 707 is covered with a conductive material.

In opposing relation to the takeup reel 700 a rotary arm 1001 is provided which is adapted to move in and out from between the flanges 700a and 700b of the takeup reel 700. The rotary arm 1001 may be shaped in a tubular configuration and is rotatably pivoted on a pin 1002 substantially parallel with the rotary shaft 701 of the takeup reel 700 in such a manner as to turn in a plane perpendicular to the shaft 701 of the reel 700 between its flanges 700a and 700b. The rotary arm 1001 carries at the free end a conductive contactor 1003 which makes contact with the bobbin 707 of the reel 700. The contactor 1003 is formed of a plurality of flexible conductive wires of, for example, 0.1 to 0.2 mm. thick. In order to mount the contactor 1003 on the rotary arm 1001, a substantially C-shaped support 1004 is mounted on the rotary arm 1001 at its free end in its lengthwise direction, and the wires are stretched in taut condition between the opposed bent plate portions 1004a and 1004b of the support 1004. For adjusting the tension of the wires they are secured at one end 1003b to the plate portion 1004b of the support 1004 and are attached, movably in the lengthwise direction of the arm 1001, at the other end 1003a to the plate portion 1004a by means of a screw rod 1005 and a nut 1006 threadably engaged therewith, as depicted in Figure 38. By clamping the nut 1006 engaged with the screw rod 1005, the wires are pulled toward the plate portion 1004a at their common end 1003a to be stretched at a predetermined tension. The length of the wires is selected greater than the discontinuous portions of the bobbin 707 defined by the sectoral plates 704 and 705 of the upper flange 700b. The contactor 1003 is formed of a plurality of wires and its length is selected greater than the width of the discontinuous portions of the bobbin 707 defined by the sectoral plates 704 and 705 of the upper flange 700b. Hence, even if the contactor 1003 engages with the bobbin 707 at the position of the discontinuous portions of the bobbin 707, the contactor 1003 makes contact with the bobbin 707 across the discontinuous portions thereof. Therefore, the discontinuous portions of the bobbin 707 are not likely to prevent engagement of the contactor 1003 with the bobbin 707. Further, since the contactor 1003 is formed of a plurality of wires, no bad contact will be caused between the contactor 1003 and the bobbin 707. Even if one of the wires is cut, the contactor can well be used in practice without causing any trouble.

While, an electromagnetic operating device 1007 is provided for driving the rotary arm 1001. Reference numeral 1008 indicates an operating rod of the device 1007, which is adapted to move in a direction indicated by an arrow in the figure when the device 1007 is energized. A spring 1010 is interposed between one end of the operating rod 1008 and a stationary part 1009, and an engaging piece 1011 mechanically coupled with the rotary arm 1001 is connected to the spring 1010 at its intermediate portion in such a manner that the rotary arm 1001 is associated with the operating rod 1008 through the spring 1010. Thus, before starting of drive of the automatic playing apparatus, namely before the tape 315 is drawn out from the cartridge 300 by the clamer 900, the electromagnetic operating device 1007 is energized to cause its operating rod 1008 to turn the rotary arm 1001, thereby urging the contactor 1003 into contact with the bobbin 707 of the takeup reel 700.

Further, the contactor 1003 and the takeup reel 700 are electrically connected to, for example, a drive control circuit of the automatic playing apparatus. The electrical connections are designed such that only when the contactor 1003 and the bobbin 707 of the takeup reel 700 makes contact with each other a closed circuit is formed and the drive control circuit operates to drive the automatic playing apparatus.

With such an arrangement, the electromagnetic operating device 1007 is energized and the rotary arm 1001 is thereby turned to bring its contactor 1003 into contact with the bobbin 707 of the takeup reel 700 before the tape 315 is drawn out from the cartridge 300. In this case, if the tape 315 does not remain on the bobbin 707, the contactor 1003 is urged into direct contact with the bobbin 707 to provide an electrical closed circuit as set forth above, so that the control circuit 1012 operates to drive the automatic playing apparatus. Accordingly, the screw rod 621 is rotated to drive the tape clamer 900, thus winding the tape 315 in the cartridge 300 on the takeup reel 700, as previously described.

If the tape still remains wound on the bobbin 707 of the takeup reel 700, the contactor 1003 is electrically insulated from the bobbin 707 by the remaining tape and hence the control circuit 1012 is not actuated to retain the automatic playing apparatus in its inoperative condition, thus ensuring that the tape in the cartridge is not drawn out.

With the above construction playing of the subsequent tape is selectively started or stopped according as the tape of the previous playing still remains wound on the takeup reel 700 or not, as has been described above. This eliminates the possibility of troubles when the tape still remains wound on the takeup reel 700.

In addition, the contactor 1003 is formed of a plurality of wires and its length is selected greater than the width of the discontinuous portions of the bobbin 707 defined by the sectoral plates 704 and 705 of the upper flange 700b. Hence, even if the contactor 1003 engages with the bobbin 707 at the position of the discontinuous portions of the bobbin 707, the contactor 1003 makes contact with the bobbin 707 across the discontinuous portions thereof. Therefore, the discontinuous portions of the bobbin 707 are not likely to prevent engagement of the contactor 1003 with the bobbin 707. Further, since the contactor 1003 is formed of a plurality of wires, no bad contact will be caused between the contactor 1003 and the bobbin 707. Even if one of the wires is cut, the contactor can well be used in practice without causing any trouble.

A detailed description will be given of a capstan drive unit 1100 which is suitable for use in this invention. The tape drive system of this invention is such that two capstans are driven by the use of separate motors to drive a magnetic tape without causing wow and flutter, in which either one of the motors is of constant-speed construction and the other is of constant-torque construction.

In magnetic tape drive system for conventional magnetic recording and reproducing devices, it is the practice to render back tension to the magnetic tape by reversing torque of a supply reel motor for avoiding the variations in tension of the tape. However, even if the reversing torque of the reel motor is constant, the back tension inevitably varies with the variations in the diameter of the convolution of the tape being wound on the reel. This introduces the variations in the travelling speed of the tape due to slip of the capstans resulting from the unstable and varying back tension. The variations of the tape speed is a harmful component in practice and causes an increase in noise. To avoid such a problem, there has been proposed in the art a closed-loop-type or two-capstan-type drive system in which the variations in the tension of the tape travelling near the magnetic head 602 due to the varying diameter of the tape winding are prevented by the provision of the first and second capstans. In the two-capstan-type drive system, however, when the tape is transported from left to right the tape is driven chiefly by the first capstan positioned on the right and the second capstan placed on the left is slightly slowed down in revolving speed to render tension to the tape, so that variations are caused in slip of the second

capstan to exert an influence upon the head. Further, the system for driving the two capstans by one drive motor is also known in the art. In this known system, however, the peripheral speeds between the drive motor and the first capstan, between the first and second capstans and between the second capstan and the drive motor vary with extension and shrinkage of the drive belt coupling the above members, by which the first and second capstans are adversely affected to produce wow and flutter. To avoid this, the present invention employs two drive motors, which will hereinbelow be described in detail.

In FIG. 39 reference numeral 315 indicates a magnetic tape which is transported in contact with a magnetic head 602 from a supply reel in a cartridge to a takeup reel. Reference numeral 1101 designates a first capstan, disposed on the side of the takeup reel with respect to the head, with which a first pinch roller 604 is urged into rotating contact. Reference numeral 1103 identifies a first flywheel affixed to the shaft of the first capstan 1101, 1104 a motor for driving the first capstan, and 1105 a belt stretched between the motor 1104 and the flywheel 1103. The belt 1105 is stretched between the rotary shaft of the motor 1104 having a small diameter and the flywheel 1103 of the first capstan having a large diameter, to constitute a constant-speed drive mechanism. Reference numeral 1102 designates a second capstan, disposed on the side of the supply reel with respect to the head, with which a second pinch roller 603 is urged into contact with the magnetic tape 315 being gripped therebetween. Reference numeral 1106 identifies a second flywheel mounted on the shaft of the second capstan 1102, 1107 a motor for driving the second capstan 1102, on the rotary shaft of which motor is mounted a flywheel 1110 of large diameter, and 1108 a belt. The belt 1108 is stretched between the large-diameter flywheel of the drive motor 1107 and the small-diameter shaft of the second capstan 1102, thus providing constant-torque drive mechanism. On both sides of the magnetic head 602 the tape 315 is gripped between the first capstan 1101 and the pinch roller 604 and between the second capstan 1102 and the pinch roller 603 to positively prevent the variations in the tape speed which might be caused by rotation of the takeup and supply reels. In this case, it is preferred to drive the second capstan 1102 with constant torque smaller than that of the first capstan 1101. To perform this, the second capstan 1102 rotating in the same direction as the first capstan 1101 is supplied with a braking force tending to turn it in a reverse direction to render tension to the magnetic tape 315 between the first and second capstans 1101 and 1102. When the first capstan 1101 and the drive motor 1104 are rotated in a clockwise direction, as indicated by full-line arrows, the braking force applying means operate in such a manner that the second capstan 1102 and the drive motor 1107 are also driven in the clockwise direction, as indicated by full-line arrows in the figure, at the same peripheral speed as that of the first capstan 1101 and that a decrease in the voltage of the drive motor 1107 yields a braking force such as shown by a broken line arrow in the figure. Since the first capstan 1101 is driven at a constant speed and the second capstan 1102 is driven with a constant torque, the tension of the tape against the head can be held constant.

With such an arrangement as described above, the travelling speed of the magnetic tape 315 on the magnetic head 602 is determined by the first capstan 1101 and the tension of the magnetic tape 315 against the head is rendered by the second capstan 1102 while at the same time being held constant at all times. At this time the tension of the tape 315 is not subject to the variations such as those by the diameter of the convolution of the tape on the reels and is held constant. Further, a desired tension can be rendered to the magnetic tape 315 by suitable selection of the torque of the second capstan 1102. The variations in the tension of the tape 315 travelling between the supply reel and the second capstan 1102 resulting from the variations in the diameter of the winding of the tape on the supply reel is completely eliminated by

the same effect of the flywheel 1106 of the capstan 1102 and the pinch roller 603 as that of an impedance roller. At the same time, once the magnetic tape 315 has been applied a tension due to its extension between the first and second capstans 1101 and 1102, the tape is driven by the first pinch roller 604 at a constant speed, while being given a constant torque by the second capstan 1102, ensuring complete elimination of wow and flutter of the magnetic tape 315 making sliding contact with the magnetic head 602. In this case, it is sufficient for the takeup reel only to take up thereon the tape supplied by the first capstan 1101, while the supply reel is required only to be supplied with a constant torque sufficient to ensure that the tape drawn out from the supply reel is driven to the second capstan 1102 without causing any trouble. Accordingly, the magnetic tape 315 can be driven to the magnetic head 602 with practically no wow and flutter. In case of driving the second capstan 1102, it is preferred, for preventing breakage of the tape at the start of the driving, to preliminarily drive the second capstan 1102 to rotate it in the same direction as the first capstan 1101 to thereby drive the first and second capstans 1101 and 1102 at the same peripheral speed. For this purpose, in FIG. 39 an idler 1109 is arranged to engage the first and second flywheels 1103 and 1106, through which the preliminary driving of the second capstan 1102 is effected at the start of the driving. After the preliminary driving the idler 1109 is disengaged from the two flywheels 1103 and 1106, and the drive motor 1107 is driven in the clockwise direction to render a braking force to the second capstan 1102.

FIG. 40 illustrates another example of the tape drive system of this invention, in which the first and second capstans 1101 and 1102 in FIG. 39 have been interchanged.

Since the present drive system employs the constant-speed and constant-torque drive motors, the tension of the tape can be held constant.

The foregoing has outlined the general construction of this invention, and a description will hereinbelow be given of the above-described apparatus together with its operations in connection with FIGS. 2 and 20.

Let it be assumed that the tape clasper 900 rests at such a position as in FIG. 20 and that the rod 802 is in contact with any of the opposed cam faces of the cam 801 and consequently the line 703 of the taken-up reel 700 lies on the line A-A, (refer to FIG. 27). Under such conditions driving of the motor 624 leads to rotation of the screw rod 621 to bring the shifting member 622 and consequently the clasper 900 to the cartridge 300, namely to the lower side in the figure. When the tape holding members 923 and 903 of the tape clasper 900 has engaged with or disposed close to the tape 315 on the cartridge 300, the motor 624 is stopped by the switch positioned on the clamp piece 919. During this, the tape clasper 900 touches the magnetic head 602, the capstans 1101 and 1102 and so on, but the movement of the tape clasper 900 is not prevented by them. Concurrently with or immediately subsequent to the stopping of the movement of the tape clasper 900, the plunger 931 of the tape clasper 900 is energized to clamp the tape 315 between the tape holding members 923 and 927 or 903 and 908. Simultaneously with or immediately after the clamping of the tape the motor 624 is driven in a direction opposite to the aforementioned one, by which the tape end portion gripped by the tape clasper 900 is drawn out from the cartridge 300 through the recess 313 and is brought to the takeup reel 700 substantially along the line 703.

When the tape clasper 900 has reached the takeup reel 700, the outside surfaces of the tape holding members 908 and 903 or 923 and 927 push open the clamp pieces 710 and 711 against the springs 712 and 713 or 716a and 716b to permit the tape to be drawn therebetween. After the tape holding members 908 and 903 or 923 and 927 have passed through between the clamp pieces 710 and 711, the tape 315 is brought to the right while being clamped between the clamp pieces 710 and 711. Finally, the shaft 930 of the clasper 900 comes to engage with the fixed member 936, by which the tape end portion is released from the holding members 903

and 908. In this manner, the tape 315 is gripped between the clamp pieces 710 and 711. In this case, when the clamer 900 has been brought to a position remote from the takeup reel 700 the motor 624 is stopped by the switch mounted on the abutment member 920, thus stopping the clamer 900.

Following this, the motor 619 is driven to disengage the rod 802 from the cam 801 mounted on the shaft of the takeup reel 700 and to bring the front cover 613 to the magnetic head 602 through the shifter rod 614. At the same time the engaging members 615 and 616 are disengaged from the engaging pieces 612 and 611 of the tension levers 605 and 606, so that the tape 315 is put into contact with the engaging members 610 and 609 of the tension levers 605 and 606. Under such conditions, the drive of the motor 619 is stopped.

Thereafter, the pinch rollers 604 and 603 are urged into rotary contact with the capstans 1101 and 1102 and, at the same time, the motor 702 of the takeup reel 700 is driven to drive the tape 315 while rendering it a predetermined tension at the position of the magnetic head 602 for recording signals on the tape or reproducing the recorded signals therefrom. At this time the magnetic tape 315 is transported as indicated by a chain line.

Upon completion of winding of the tape 315 on the takeup reel 700 (in this case the tape end should still remain on the reel 304 of the cartridge 300), the pinch rollers 603 and 604 are disengaged from the capstans 1101 and 1102 and the plunger 1007 is energized to disengage the tape 315 from the magnetic head 602, under which conditions the rewinding motor 501 provided on the side of the cartridge 300 rotates to drive the reel 304 in a rewinding direction. Thus, the tape 315 wound on the takeup reel 700 is rewound on the reel 304 under such a condition as indicated by the broken line in FIG. 20. After the rewinding of the tape 315, the plunger 1007 is deenergized by a signal fed from the electrical circuit which is controlled by an electrical signal, obtained by the contact mounted on the free end of the rotary arm 1001. In this case, since the rotary arm 1001 is coupled with the elastic belt 1011b, vibration produced in the bobbin 707 of the takeup reel 700 by the contact of the free end of the rotary arm 1001 can be effectively prevented. The vibration is due to the fact that the bobbin 707 is discontinuous as described above and consequently its central aperture 706 is not formed over the entire rotational angular range of the bobbin 707. The deenergization of the plunger 1007 is followed by energization of the motor 619, by which the rod 802 is moved into engagement with the cam 801 mounted on the shaft of the takeup reel 700 to bring the takeup reel 700 back to its initial position, while at the same time bringing the front cover 613 away from the magnetic head 602 and returning the tension levers 605 and 606 to their initial positions by the shifter rod 614.

After the tape 315 has been rewound on the reel 304 in the cartridge 300 in the manner described above, the cartridge 300 is brought out of position into a case 1200 located, for example, under the panel 601. A description will be made in connection with means for this purpose. That is, after the rewinding of the tape 315 on the reel 304 the cam 440 turns in a counterclockwise direction, as depicted in FIG. 10, and the upper portion of the cartridge 300 is slanted forwards, for example, through an angle of 5 degrees or so by the second cam face 440b of the cam 440. As a result of this, the cartridge 300 is moved away from the panel 601 and the support plate 436 is brought down under such conditions.

Means for bringing down the support plate 436 comprise a screw rod 1201 extending vertically in the lower portion of the rack 1 and a guide rod 1202 extending parallel with the screw rod 1201, which are secured to the rack 1 by means of an angle 1203 and a bearing 1204, as illustrated in FIGS. 2 and 3. A moving member 1205 is mounted on the screw rod 1201 and the guide rod 1202 in such a manner as to be moved up and down by rotation of the screw rod 1201, and a cam motor 439 having mounted thereon the aforementioned cam 440 and the rotary shaft 437 of the support plate 436 are attached to the moving member 1205. Reference numeral 1206 designates a motor for driving the screw rod 1201.

The cartridge 300 thus lowered by the support plate 436 is brought to a place opposite to one opening portion of the case 1200 by the stopping of the screw rod 1201. The case 1200 is generally shaped in a tubular configuration, whose cross section

5 is conformed to the cartridge 300. The case 1200 consists of upper and lower wall portions 1200a and 1200b (refer to FIG. 2) and end faces 1200c and 1200d opposed to the opening portion. The upper wall portion 1200a is secured to the rack 1 by suitable angles 1207 and a plurality of guide rollers 1208 are mounted by the angles 1207 on the inside of the joining portion of the upper wall portion 1200a with the lower wall portion 1200b. The pair of recesses 317 of the cartridge 300 put in the case 1200 engage with the guide rollers 1208 and a recess 1209 is provided in the bottom of the rack 1 at a place corresponding to the underside of the lower wall portion 1200b, in which recess rollers 1210 are provided. The lower wall portion 1200b is adapted to be positioned relative to the upper wall portion by the pair of angles 1207. Reference numeral 1211 designates means for fixing the lower wall portion 1200b to the rack 1.

Accordingly, the cartridge 300 brought by the support plate 436 to a position corresponding to the opening of the case 1200 is pushed from the support plate 436 into the case 1200 by the rotation of the cam motor 439 and consequently by the fourth cam face 440d due to rotation of the cam 440. At this time the pair of recesses 317 of the cartridge 300 are guided by the guide rollers 1208, ensuring that the cartridge 300 is smoothly pushed into the case 1200 without falling down. In FIG. 2 there is illustrated in the left-hand case 1200 the cartridge 300 put therein in the foregoing manner and the support plate 436 is shown to lie in its lowered position. Thus, the cartridges are sequentially brought into the case 1200 after the tapes loaded in the cartridges were played. In this case, the provision of a switch (not shown) on the closed end face 1200c or 1200d of the case enables indication of the time when the case has been packed with the cartridges to capacity.

Thus, the fixing means 1211 is released, if necessary, and the lower wall portion 1200b is pulled out from the rack 1. At 40 this time the cartridge 300 supported by the rollers 1208 is pushed by the closed end face 1200d and is thereby disengaged from the rollers 1208 and is then pulled outside while being placed on the lower wall portion 1200b, namely with the upper half portion of the case 1200 being removed. Therefore, 45 the cartridge 300 can be readily taken out from the lower wall portion 1200b.

After removal of the cartridges from the case the lower wall portion 1200b is inserted again into its initial position.

In the example illustrated in FIG. 2, while the magnetic tape 315 is driven in either one of the panels 601, namely the player is in its operative condition, the cartridge 300 containing the tape 315 for the next playing is brought by the shifting support 403 to a position corresponding to the other panel 601. Then, the cartridge 300 is held in such a condition as depicted in FIGS. 9 and 12, and the magnetic tape end portion is drawn out from the cartridge 300 to be held on the takeup reel 700. Namely, under such conditions the driving mechanism of this panel is held in its standing-by condition. Upon detection 55 of a signal indicating completion of the playing of the one panel 601 (which signal can be previously recorded, for example, on the magnetic tape 315), driving of the other panel is initiated to start the following playing. During this playing, in the one panel the cartridge loaded with the tape previously played is brought into the case 1200, after which the lift unit 100 is driven by the motor 201 to move the lift guides 101L and 101R by one pitch, and then the cartridge 300 for the next playing is brought to the predetermined playback position as 60 previously described. Such operations are repeated, by which the plurality of cartridges 300 arranged one on another are continuously played in a predetermined sequential order, thereafter being sequentially brought into the case.

In accordance with this invention magnetic tapes loaded in a plurality of cartridges can be automatically played one after another.

It will be apparent that many modifications and variations may be effected without departing from the scope of the novel concepts of this invention.

We claim as our invention:

1. An automatic tape playback apparatus having a frame and comprising a pair of tape playback units, a plurality of cartridges, a plurality of reels each mounted in said cartridges and each containing a recorded magnetic tape, means for arranging said plurality of cartridges in the order of a program, means for automatically alternately positioning said plurality of cartridges at said pair of tape playback units, takeup reels mounted on said tape playback units, means provided on said tape playback units for feeding a tape from a cartridge into each of said tape playback units and to said takeup reels without requiring a leader on the tape, clamping means provided on said takeup reels for automatically clamping said tape, and a pair of playback means for automatically playing back signals recorded on said tapes, mounted on each of said tape playback units.

2. An automatic tape playback apparatus as claimed in claim 1, wherein means are provided for rewinding the tape from one of said takeup reels into said cartridge after said tape has been played back, and means for moving said cartridge to a cartridge stored position.

3. An automatic tape playback apparatus as claimed in claim 1, wherein means are provided for positioning said takeup reels, a plurality of rotary shafts upon which said takeup reels are mounted, each of said positioning means consisting of a first means fixed to one of said rotary shafts and a second means engaging said first means to move each of said takeup reels to a predetermined position.

4. An automatic tape playback apparatus as claimed in claim 3, wherein said first and second means are cams.

5. An automatic tape playback apparatus as claimed in claim 2, wherein means are provided for detecting the presence of magnetic tape wound on each of said takeup reels.

6. An automatic tape playback apparatus as claimed in claim 5, wherein said detecting means consists of a rotary arm one end of which is pivoted to said frame, a plurality of conductors supported at the other end of said arm and hubs of each of said takeup reels with the outer periphery of said hubs being made of conductive material.

7. An automatic tape playback apparatus as claimed in claim 1, wherein said tape clamping means comprises a tape holding means, a means for operating said tape holding means, and a means for moving said tape holding means between said cartridge in playback position and said takeup reel.

8. An automatic tape playback apparatus as claimed in claim 1, wherein each of said tape playback units comprises first capstans driven at constant speed, second capstans driven in constant torque, first pinch rollers engaging said first capstans, second pinch rollers engaging said second capstans, and magnetic heads disposed between said first and second capstans.

9. An automatic tape playback apparatus having a frame and comprising a pair of tape playback units, a plurality of cartridges, a plurality of reels each mounted in said cartridges and each containing a recorded magnetic tape, means for arranging said plurality of cartridges in the order of a program, means for automatically alternately positioning said plurality of cartridges at said pair of tape playback units, takeup reels mounted on said tape playback units, means provided on said tape playback units for feeding a tape from a cartridge into each of said tape playback units and to said takeup reels, clamping means provided on said takeup reels for automatically clamping said tape, and a pair of playback means for automatically playing back signals recorded on said tapes, mounted on each of said tape playback units.

10. A cartridge for use with an automatic tape playback apparatus comprising a conventional reel rotatably supported within said cartridge, a magnetic tape wound on said reel, a recess formed in said cartridge from which said tape may be withdrawn, an aperture formed in said cartridge through which said reel may be rotated by a rotating means, means for clamping said reel when said cartridge is not positioned in a playback position comprising spring means urging said reel against the periphery of said cartridge around said aperture and a brake shoe mounted about said periphery of said aperture on said cartridge to engage said reel when it is not being rotated by said rotating means, a guide means mounted in said cartridge, means for clamping a free end of said magnetic tape, and said tape passing through said guide means across said recess.
